UNITED STATES PATENT OFFICE.

HARRY M. HAUN, OF ETHANAC, CALIFORNIA.

BALL-BEARING DOOR-HANGER.

1,045,284.

Specification of Letters Patent. Patented Nov. 26, 1912.

Application filed May 21, 1912. Serial No. 698,786.

To all whom it may concern:

Be it known that I, HARRY M. HAUN, a citizen of the United States, residing at Ethanac, in the county of Riverside, State 5 of California, have invented certain new and useful Improvements in Ball-Bearing Door-Hangers; and I do declare the following to be a clear, full, and exact description of the same, such as will enable others 10 skilled in the art to which it appertains to make and use the same, reference being had to the accompanying drawings, and to the characters of reference marked thereon, which form a part of this application.

15 This invention relates to improvements in sliding hanger doors, the object of the invention being to produce a ball-bearing hanger for the door which will operate in a specially designed form of track way where- 20 by the door can be moved along the track with ease and precision and with a minimum amount of friction and labor.

A further object of the invention is to 25 produce a ball bearing hanger for the door wherein the door will operate in a straight and true track which will render the device capable of operating with a minimum amount of friction and which will reduce the necessity of replacing due to the fact 30 that there will be no swinging or vibration of the door on its bearings.

Also a further object of the invention is to 35 produce such a structure as will be strong and durable and one which will stay in true position when once installed.

40 A further object of the invention is to produce a simple and inexpensive device and yet one which will be exceedingly effective for the purposes for which it is de- signed.

These objects, I accomplish by means of such structure and relative arrangement of the parts as will fully appear by a perusal of the following specification and claim.

45 On the drawings similar characters of reference indicate corresponding parts in the several views.

Figure 1 is a front elevation of a door 50 showing the same in position with my improved hanger and track connected therewith. Fig. 2 is a sectional view taken on a line X—X of Fig. 1. Fig. 3 is a sectional view of a detached portion of the track and door taken on a line Y—Y of Fig. 2. Fig. 55 4 is a fragmentary part of a door and

hanger showing a modified form of hanger from that shown in Fig. 3. Fig. 5 is a top plan view of a circular track way adapted for use with a circular door as will appear.

Referring now more particularly to the characters of reference on the drawings, the numeral 1 designates a building having the usual door opening adapted to be closed by a sliding door 2.

My invention embodies first a track member consisting of an upper inclosing member 4 provided with an inner groove 5, such member 4 having projecting flanges 6 and 6^a bolted to which are supporting bars 7 and 8, such bars 7 being bolted to the building 1 in a perpendicular manner and the bars 8 curving outwardly over the member 4 and being bolted to the members 7 and 1. Bolted to the member 6 is a flange 9 having a curved portion 10 and bolted to the member 6^a is a flange 11 provided with a curved portion 12 spaced from the portion 10 to form a slot 13.

The numeral 14 designates the hanger proper which will be provided with holes 15 to receive balls 16. These balls will fit snugly in the holes 15 and both the balls and the holes will be strictly smooth on their surfaces in order that there may be a minimum friction between them. The balls 16 will fit snugly into the curved surfaces of the members 10 and 12 and the hanger 14 will project through the slot 13 and be connected with the door 2 by means of bolts or similar fastening structure.

In practice the bolts 11^a which project through the member 11 and through the member 6^a pass through elongated slots 11^b in said member 11, whereby such member 11 will be adjusted to make the slot 13 of just a sufficient width to receive the hanger 14 sufficiently close to prevent any vibration or swinging of such hanger with the weight of the door and to cause it to run in a true and accurate manner. This 100 adjustment of course would only be used in case the parts became loose by reason of wear on the balls or the runways.

The width of the hanger 14 is substantially a one-third of the diameter of the 105 balls 16 thus permitting one-third of the balls 16 to project on each side of the hanger 14 thus distributing the bearing of the balls equally between the hanger and the track way to cause the track and balls to move 110

easily and with a minimum amount of friction.

In each end of the track-way, is a small hole 17 through which may be projected pins 18 to form a stop or closure at the end of the track-way to prevent the hangers from running out of the track. If the track-way were made in several sections then each section would be provided with these holes 17 in each end in order to cause no confusion in setting up the track, but the pins of course would be only set through the ends of the installed track. I may have for some use a curved track-way 19 and a corresponding curved door as shown in Fig. 5 in which event I would use a hanger 20 provided with a single ball 21, the rest of the structure being the same as shown for the other views.

Of course the track-way and the hangers and the balls will be of any size desired or of any material desired but preferably of such size and such material as will make the same as light as possible and still be sufficiently strong and have but a minimum amount of friction between the parts.

The hangers 14 will of course project at a slight distance above the ball 16, in fact only

such a distance as will supply the necessary strength for the device.

While this specification sets forth in detail the present and preferred construction of the device, still in practice such deviations from such detail may be resorted to as do not form a departure from the spirit of the invention.

Having thus described my invention what I claim as new and useful and desire to secure by Letters Patent is:

A device of the character described comprising an upper inclosing member provided with a groove in its under face, a projecting flange on each side of said member, a track-way comprising two curved members spaced apart and secured to said projecting flanges, hangers projecting between said curved members and provided with holes, balls mounted in said holes and bearing against said curved members, and a door swung on said hangers, as described.

In testimony whereof I affix my signature in presence of two witnesses.

HARRY M. HAUN.
